7 Claims. (Cl. 256—20)

The invention relates to a back-coupling arrangement for a receiver without transposing the received frequency or with transposing the received frequency f_e to a higher or lower intermediate frequency f_z by means of a local oscillation frequency f_{lo} . The connection systems according to the invention possess the following essential advantages in comparison with the known connections:

10. 1. A considerably increased degree of amplification (reckoned as the ratio between the intermediate frequency amplitude A_z and the receiving amplitude A_e),
2. An increased selectivity,
15. 3. Elimination of the radiation of the local oscillation f_{lo} .

According to the invention the degree of amplification and selectivity is increased by using back-coupling for the receiving frequency or for the intermediate-frequency and by extending this back-coupling to such a degree that normally self-excitation would take place. This self-excitation is prevented by causing the tube to oscillate with a frequency greater than the back-coupled frequency.

The principle according to the invention will be best explained in conjunction with the connection systems according to the annexed Figures 1-4, in which exemplary embodiments of transposition connections are shown.

Fig. 1 shows a circuit diagram of a superheterodyne receiver according to the invention.

Fig. 2 shows a circuit diagram of a receiver without using transposing the frequency.

Fig. 3 shows a superheterodyne receiver with two mixing tubes in push-pull connection and

Fig. 4 shows a modification of the circuit of Fig. 3.

In particular with reference to Fig. 1 a local oscillator 1 with screening grid, and preferably with twin control grids 2 and 3, is in self-excitation with the natural wave of the circuit 4, 5, and thus produces the frequency f_{lo} . The superimposed connection is built up as capacitative or inductive three-point connection, whereby the capacitative connection is preferably employed for short to ultra-short waves, and the inductive connection for long waves. At a centre-tapped point 6 of this local oscillation circuit there is coupled the intermediate frequency circuit 7, 8. The feeding of this circuit with the anode potential or the dynamic earthing of this circuit through the medium of the blocking condenser 9 also takes place in a centre-tapped point of the circuit.

The operation of the exemplary embodiment of an arrangement according to the invention may be clearly understood by the following explanations with respect to Fig. 1. The input circuit 15, 16 is tuned to the frequency value of the oscillations to be received and leads via condenser 19 to one grid (2) of the mixing stage 1, said grid (2) being supplied with a suitable bias via the resistance-arrangement 17, 18. The other grid (3) of said mixing stage 1 is connected by 10 means of the coupling-condenser 11 and the oscillatory circuit 4, 5 with the anode of valve 1. This oscillatory circuit is tuned to a very high frequency f_{lo} , which represents the superheterodyne frequency.

In view of the inherent capacities of the valve 1 between the grids 2 and 3 and the anode of said valve the circuit generates the frequency f_{lo} and simultaneously the input grid 2 controls the electron stream of valve 2, such producing in the anode circuit of valve 1 an intermediate frequency by superheterodyne effect which is dependent on the natural frequency value of the oscillatory circuit 4, 5 and the received input oscillations. The anode circuit of said mixing stage 1 is completed by a resonant circuit 7, 8 tuned to the arising intermediate frequency having a lower value than the superheterodyne frequency f_{lo} and connected between a centre-tap of coil 5 and earth, said circuit 7, 8 having a 15 centre tap of its coil earthed by means of a condenser 9. In order to obtain a large amplification degree for the desired intermediate frequency f_z a back-coupling is used between the oscillatory grid and circuit and the anode circuit 20 for the intermediate frequency by means of condenser 10. This back-coupling effect may be increased in such a manner that, normally, if the oscillatory circuit 4, 5 would not exist in the anode circuit, a self-oscillating effect with respect to 25 the intermediate frequency would arise. Since in this case of self-oscillating in the frequency f_z this frequency f_z could not be further used in the associated circuit, this self-oscillating of the intermediate frequency f_z must be prevented which 30 is realized by the use of the oscillatory circuit 35 tuned at a frequency value much greater than that of f_z . It is known to persons of ordinary skill in the art that in view of the self-oscillating effect of the valve 1 in the frequency f_{lo} having 40 a greater value than that of the frequency f_z a self-oscillating of the oscillation having the frequency f_z is prevented. In view of this effect it 45 is possible to make the degree of the back-coupling extremely high, i. e. these circuits are firmly 50

55

coupled, such producing a high amplification for the amplitudes of the intermediate frequency f_z which is most important for the efficiency of the circuit arrangement, such high degree of back-coupling being impossible in normal circuits without using the circuit 4, 5 tuned to a frequency higher than the desired frequency to be used in the associated stages.

The centre-tapped connections are required for the feed-supply of the anode of valve 1 for preventing detrimental effects upon the resonant circuits by unsymmetrical conditions.

The circuit 7, 8 is coupled inductively with a band-filter output circuit 13, 14, which is also tuned to the frequency f_z . The amplification of the mixing stage 1 may be additionally regulated without interruption of the oscillations by means of a potentiometer 17 connected with the negative pole of the anode current source through the medium of a grid resistance 18 in place of which, as well known, there may also be employed an automatic regulating means.

The condenser 20 may be used for neutralizing the currents of the oscillatory frequency f_u coupled by the inherent capacities of the valve to the input-grid circuit, such preventing radiating of the local oscillations by the aerial.

The considerable improvement in the efficiency of a connection system according to the invention asserts itself in comparison with the known connections principally because the intermediate frequency circuits in the usual combined detector oscillator circuits are, owing to the presence of very powerful amplitude in the connected mixing tubes, always loaded by extensive auxiliary damping from the tube, which may also be compensated by the method of back-coupling arrangement according to the invention.

Elimination of the radiation of f_u from the aerial is accomplished in accordance with the invention by a condenser 20, which compensates the component potential of A_{ui} transmitted by the internal capacity 21 between the twin grids by a counter-phasic coupling from the anode.

The invention may also be employed as sensitive, back-coupled single circuit receiver without utilizing a frequency transposition. For this purpose with reference to Fig. 2 the circuit 15, 16 coupled with the aerial and also circuit 7, 8 shown in Fig. 1 is tuned to the receiving frequency. The short-wave oscillation circuit 4, 5 is tuned to a wave which is shorter than any wave which may be received. Short wave oscillations generated by the circuit 4, 5 prevent in accordance with the invention the self-excitation of the receiving frequency, and there is obtained at the circuit 7, 8 a considerable selectivity and high-frequency amplification without cause for anxiety that this circuit might undergo self-oscillation. It is possible to transmit the amplified receiving-high frequency to a circuit 7a, 8a, coupled with the circuit 7, 8 and to rectify in a separate tube connected with the circuit 7a, 8a, or rectification may be performed in the same tube by means of audion connection shown in Fig. 2 or by means of the twin grid connection 2 shown in Fig. 1. A special manipulation regulation of the back-coupling between the circuits 15, 16 and 7, 8 is unnecessary in the circuit according to the invention even upon variation of the received wave, which represents a considerable improvement as compared with the known back-coupling connections without a short auxiliary wave.

When using a twin-grid tube shown in Fig. 1 the control efficiency for each control grid is

halved because each of both control grids is passed only by one half of the electronic stream. According to an additional feature of the invention, it is possible to operate with full control efficiency by using circuits with two tubes in push-pull connections shown in Figs. 3 and 4. The desired intermediate frequency potential A_z is tapped as the difference potential of the anodes of the two mixing tubes in relation to each other. The input receiving potential is passed to each grid in counter-phase if the superposition on both grids is co-phasic or if necessary reversed. The first method is employed according to Fig. 3 primarily in the case of infradyne connections, in which the intermediate frequency f_z to be obtained is in the order of the local oscillation f_u , and the latter on the other hand in superheterodyne receiver connections, in which f_z is much longer than f_u .

Fig. 3 shows two mixing tubes 22 and 23, for example twin-grid tubes. Single-grid tubes, however, are also suitable, and these may then have twice the steepness. The anodes of these tubes are connected through the medium of an intermediate frequency circuit comprising the condenser 24, the coil 25, and the differential capacity 26 forming a part of the oscillatory circuit capacity. The self-excitation of the tubes takes place through the oscillatory circuit 27, 28 in equal cadence for both grids. For this purpose the coil 28 is tapped at the centre, or the condenser 27 earthed at the centre (differential condenser). The feeding of this local oscillation f_u occurs in each case through a part-plate 29 or 30 of a differential condenser. The additional back-coupling for the intermediate frequency in accordance with the invention may be established and regulated through the medium of another plate-armature 31 or 32 of the same differential condenser by connection in each case with the anodes of the other tube. The oscillatory grids are leaked off over resistances 33, 34, whereby a very desirable negative charging of the same is capable of being adjusted. The reception is fed in counter-cadence from the aerial circuit 41 over the circuit 35, 36, whereby this circuit is earthed at the centre through the medium of a condenser 37, and a regulable negative grid bias passed to the same through the medium of a series resistance 38. The feeding of the tube with the anode potential takes place at the centre of the intermediate circuit coil 25. This supply circuit damps the local oscillation frequency f_u produced in cadence, and must, therefore, be supplied through the medium of a resistance 39, which is large for this frequency. For this purpose there may also be employed the part windings of the choke 25. The connection system has the advantage of a complete de-coupling of the intermediate frequency circuit from the local oscillation circuit even in the case of slight difference in frequency between the same. A band filter output circuit 40 is coupled with the circuit 24, 25. In the circuit 40 the induced E. M. F. is proportional to the input receiving potential and disappears if the input receiving potential in the circuit 35, 36 disappears. Beyond this the aerial 41 coupled with the circuit 35, 36 is in each case free of radiation as compared with the heterodyne wave.

Fig. 4 shows an additional push-pull connection, which is particularly suitable for superheterodyne receiver connections, in which f_z is greatly different to f_u . The receiving circuit 42, 43 is coupled with the tubes 44, 45 in cadence,

so that its full potential reaches the grids of these tubes. The tubes are in counter-cadence self-excitation on the local oscillation frequency f_L of the circuit 46, 47. The electrical centre of 46, 47 is found by a differential condenser 48, so that the connection is again free of radiation against the local oscillation. If twin grids 49, 50 are provided, this differential condenser may be omitted and wiring performed as shown in broken lines. Automatic or manually operated volume control may then be introduced proceeding from a counter-potential 51. Otherwise this bias should be applied in common to the grids shown in solid lines. The self-excitation takes place through the medium of two small condensers 52, 53 (approximately 10 cm.), for example Mesny condensers. Two oscillatory chokes 54, 55 ensure that potentials of the high local oscillation frequency are able to build up in sufficient amount at the anodes. They allow, however, the long-wave intermediate frequency f_I to reach the circuit 56, 57 without being weakened. Two larger condensers 58, 59 (approximately 50 cm.) may then be employed for the additional back-coupling of the intermediate frequency f_I according to the invention. Its simultaneous superposition to the already existing grid potentials of the frequency f_L takes place in the form of embodiment according to Fig. 3 by capacitative distribution of potential, whereby the small condensers 60, 61 (approximately 10 cm.) ensure that the back-coupled intermediate frequency potential is not possibly short-circuited by the local oscillation circuit 47, 46. The same purpose is served by the series resistances 62, 63 of approximately 1000 ohms, which cause the local oscillation frequency f_L not to be possibly interrupted upon the application of the intermediate frequency back-coupling 58, 59 owing to short-circuiting of the oscillatory chokes 54, 55. Naturally the same result may also be obtained by methods known per se of mixing two greatly differing frequencies. In place of the capacitative back-coupling it is also readily possible to employ an inductive back-coupling, and in place of the stated parallel feed of the two oscillatory grids there may also readily be employed a series feeding of the same. A band filter 64, 65 is coupled with the intermediate frequency circuit 56, 57, and allows the intermediate frequency to be tapped without interfering traces of local oscillation frequency.

According to the invention, the fading regulation may extend not only to the twin grids 49, 50 but at the same time also to the oscillator grids, as in the stated connection the beginning of the generation of the oscillations is very soft, more particularly when using audion combination with highly ohmic resistances 66, 67. An additional advantage of this connection system is the elimination of certain harmonics of the superposition and the reception, and accordingly a reduction in the number of the usual "whistling points" in the superheterodyne receiver. The feeding with anode current does not damp any of the existing oscillations with the exception of the received wave, which is amplified directly in cadence, this being in any case desirable. The blocking condenser 68 causes a dynamic earthing of the circuit middle point of f_I .

In the case of all connections referred to the possibility is provided fundamentally of adjusting the selectivity of a heterodyne receiver by hand by a special adjustment knob (the back-coupling passage of f_I). The simultaneously in-

creasing amplification may in accordance with the invention be kept down by means of a sound-regulating device in the apparatus. A receiving apparatus is accordingly provided, the selectivity of which may be adjusted by hand according to requirements in individual cases. In the case of a close coupled band filter cascade as hitherto usual these possibilities do not exist. In face of these connections the method according to the invention possesses the additional advantage of a great decrease in the number of circuits. As compared with the known methods of eliminating loss by back-coupling, the method according to the invention offers the considerable advantage that even in the case of exaggerated back-coupling a self-excitation of the oscillatory circuit free of attenuation is unable to occur, as this is always withheld by the local oscillation.

I claim:

1. In a radio-receiver an electronic valve having a cathode, an anode and at least two control-grids, a receiving input circuit coupled with an aerial circuit and connected with said cathode and one of said control grids, an oscillatory circuit tuned to a frequency greater than the receiving frequencies and connected with said anode and the other of said control grids, a back-coupling circuit for the receiving frequency connected with a tapped-point of said oscillatory circuit and an anode current source and firmly coupled with said receiving input circuit.

2. In a superheterodyne receiver an electronic valve having a cathode, an anode and at least two control-grids, a receiving input circuit coupled with an aerial circuit and connected with said cathode and one of said control-grids, an oscillatory circuit for producing an intermediate frequency connected with said anode and the other of said control-grids, an intermediate frequency circuit connected with a tapped-point of said oscillatory circuit, a back-coupling circuit for said intermediate frequency, said oscillatory circuit tuned to a frequency greater than the intermediate frequency, therefore generating oscillations preventing self-excitation for the intermediate frequency.

3. In a superheterodyne receiver an electronic valve having a cathode, an anode and at least two control-grids, a receiving input circuit coupled with an aerial circuit and connected with said cathode and one of said control grids, an oscillatory circuit for producing an intermediate frequency connected with said anode and the other of said control-grids over a block-condenser, an intermediate frequency-circuit connected with a tapped-point of said oscillatory circuit and over a variable condenser with said second control grid and over a resistance with said cathode, therefore effecting a back-coupling for the intermediate frequency, a tapped-point of said intermediate frequency circuit connected over a resistance with an anode-current source and over a condenser with an earthing point, said oscillatory circuit tuned to a frequency greater than the intermediate frequency, therefore generating oscillations preventing self-excitation for the intermediate frequency.

4. In a superheterodyne receiver an electronic valve having a cathode, an anode, and at least two control-grids, a receiving input circuit coupled with an aerial circuit and connected with said cathode and one of said control-grids, an oscillatory circuit for producing an intermediate frequency connected with said anode and the

other of said control-grids over a block-condenser, an intermediate frequency-circuit connected with a tapped-point of said oscillatory circuit and over a variable condenser with said second 5 control grid and over a resistance with said cathode, therefore effecting a back coupling for the intermediate frequency, a tapped-point of said intermediate frequency connected over a resistance with an anode-current source and over 10 a condenser with an earthing point, said oscillatory circuit tuned to a frequency greater than the intermediate frequency, therefore generating oscillations preventing self-excitation for the intermediate frequency, said intermediate frequency circuit being coupled with a band-filter 15 output circuit.

5. In a superheterodyne receiver an electronic valve having a cathode, an anode and at least two control-grids, a receiving input circuit coupled with an aerial circuit and connected with 20 said cathode and one of said control grids, an oscillatory circuit for producing an intermediate frequency connected with said anode and the other of said control-grids over a block-condenser, an intermediate frequency-circuit connected with a tapped-point of said oscillatory circuit and over a variable condenser with said 25 second control grid and over a resistance with said cathode, therefore effecting a back-coupling for 30 the intermediate frequency, a tapped-point of said intermediate frequency connected over a resistance with an anode-current source and over a condenser with an earthing point, said oscillatory circuit tuned to a frequency greater 35 than the intermediate frequency, therefore generating oscillations preventing self-excitation for the intermediate frequency, said intermediate frequency circuit being coupled with a band-filter output circuit, the internal capacity between 40 said control-grids being compensated by a neutrodyne condenser.

6. In a superheterodyne receiver two electronic valves, each of which having a cathode, an anode and at least two control grids, a receiv-

ing input circuit coupled with an aerial circuit and connected with the control grids of said valves, the control grids of said valves connected over differential condensers with each other, with the one side of an oscillatory circuit for producing 5 an intermediate frequency and with an intermediate frequency circuit, the other side of said oscillatory circuit connected over a differential condenser with the mid-point of said intermediate frequency circuit, a tapped point of 10 said intermediate frequency circuit connected with an anode-current source, the cathodes of said valves connected with each other, with the earthing point, with the midpoint of said oscillatory circuit and over a condenser with the mid-point of said receiving input circuit, said oscillatory circuit tuned to a frequency greater than 15 the intermediate frequency therefore generating oscillations preventing self-excitation for the intermediate frequency.

7. In a superheterodyne receiver two electronic valves each of which having a cathode, an anode and at least two control grids, one control grid of one of said valves connected with one control-grid of the other of said valves and 20 with a receiving input circuit coupled with an aerial circuit, the other control grids of said valves connected over block-condensers with an oscillatory circuit and over small condensers with an anode of the other valve, an intermediate 25 frequency circuit connected over oscillating coils with the anode of said valves, a tapped point of said intermediate frequency circuit connected with an anode-current source, the cathodes of said valves connected with each other, 30 with the earthing point, with the mid-point of said oscillatory circuit and over a condenser with the mid-point of said receiving input circuit, said oscillatory circuit tuned to a frequency greater 35 than the intermediate frequency therefore generating oscillations preventing self-excitation for 40 the intermediate frequency.

KURT SCHLESINGER.
